UNITED STATES PATENT OFFICE.

VANCE SHEARER, OF NEW YORK, N. Y., ASSIGNOR TO BLUETRUE MOTOR SPECIALTIES CORP., OF NEW YORK, N. Y., A CORPORATION OF NEW YORK.

IGNITION TIMER FOR INTERNAL-COMBUSTION ENGINES.

Application filed April 4, 1921. Serial No. 453,459.

To all whom it may concern:

Be it known that I, VANCE SHEARER, a citizen of the United States, and resident of the borough of Manhattan, in the city, county, and State of New York, have invented an Improvement in Ignition Timers for Internal-Combustion Engines, of which the following is a specification.

My invention relates to devices for controlling the ignition in multiple cylinder internal combustion engines, and particularly to the brush or movable contact and its carrier, and one object is to provide a brush that will have a smooth and even bearing upon the fixed contacts during the revolution of the timer shaft; another object is to prevent oil reaching the brush or its raceway and the fixed contacts, and further to provide a secure holder for the brush, and to facilitate the placing of the timer in position for use, without injury to the brush, which with brushes of the ordinary character heretofore in use is sometimes difficult owing to the position occupied by the timer, particularly on the Ford cars.

In the accompanying drawing:

Figure 1. is an inner end view of a timer embodying my invention, the shaft being in section.

Fig. 2. is a vertical section on the broken line 2—2 of Fig. 1.

Fig. 3. is a face view of the brush and its carrier, detached, and

Fig. 4. is an enlarged sectional view taken on the broken line 4—4 of Fig. 3.

Similar reference characters denote like parts throughout the several views.

The body 10 of the timer, is substantially hollow, and externally of a shape similar to the present standard Ford timer, and is provided with the usual lug 11, having an opening 12, to receive the connection for adjustment to advance or retard the spark. This body member is preferably of hard fiber or like insulating material, and is molded or pressed to shape, being at one side interiorly rabbeted forming an annular raceway 13, into which are seated quadrantly spaced fixed contact blocks 14, 15, 16 and 17, which are preferably pressed into place at the time of molding the body member, the outer surface of such contact blocks being flush with the surface of the raceway 13. Two metallic blocks 18 and 19, are also set into the race-

way 13, but not extending to the surface 55 thereof.

Spaced binding posts 20 and 21, are mounted on the top of the body member 10, and their terminals 22 and 23, pass through openings in said body and come into contact 60 with the two fixed upper contact blocks 14 and 15.

The binding posts 24 and 25 for connection with the two lower contacts 16 and 17, are also mounted upon the top of the body 65 10, between the binding posts 20 and 21.

Conductor wires or strips 26 and 27 pass from the lower contact blocks 16 and 17, to the contact blocks 18 and 19, into contact with which the terminals 28 and 29, of the 70 binding posts 24 and 25, are brought, these terminals passing through openings in the body 10. The strips or wires 26 and 27, are preferably pressed into place at the time of molding the body member, and extend past 75 the upper contact blocks 14 and 15, but insulated therefrom.

30, indicates the timer shaft, one end of which extends into the hollow body 10.

The carrier for the brush or movable contact 31, comprises a circular disk or plate 32, fixed to or integral with a hub 33, keyed or otherwise fixed to the shaft 30, within the hollow body 10. The edge of the disk 32, is bent over at right angles forming an 80 annular flange 34. This disk and its flange prevents oil reaching the brush or its raceway and the fixed contacts. A portion of the disk is thickened within the flange, such thickened portion 35, preferably extending 85 from the hub 33, transversely to a point closely adjacent the flange 34. A recess 36 is formed in the disk 32, adjacent the outer end of such thickened portion, into which fits a collar 37, surrounding the brush or movable contact 31. This collar is provided with a right angle annular flange 38, which rests upon the face of the disk when the collar is forced down into said recess.

This collar is also provided with an internal annular shoulder 39, against which the annular flange 40, on the bottom of the brush 31, contacts, the brush being inserted into the collar from the under side thereof, and projecting outwardly therefrom, but 90 positively retained in position by said flange and shoulder.

A spiral spring 41, within said collar,

bears against the back of the brush and the bottom of the recess 36, giving the brush a resilient bearing upon the surface of the raceway 13.

5. A lock nut 42, may be employed upon the shaft 30, forward of the carrier hub 33.

My construction of brush carrier protects the movable and fixed contacts and the raceway against oil that may be carried 10 along the rotary shaft. The brush is securely retained in its carrier, and the placing of the timer in position for use is greatly facilitated.

I claim as my invention:

15. 1. In an ignition timer, the combination of a body having an interior annular raceway, spaced contacts embedded therein, a rotary shaft extending into the body, a circular metallic plate fixed to the shaft and 20 provided with a recess adjacent its outer edge, a sleeve fitted within said recess having an outer annular flange bearing upon the face of said plate and provided with a central opening of less diameter than its 25 body, forming an interior annular shoulder,

a brush projecting through said opening provided with an annular flange on its rear end taking against said shoulder, and a spring within said sleeve bearing upon the flanged end of the brush.

30. 2. In an ignition timer, the combination of a body having an interior annular raceway, spaced contacts embedded therein, a rotary shaft extending into the body, a circular metallic plate having a hub fixed to the shaft, its outer edge being bent at right angles on one side and having a recess adjacent said edge, a sleeve fitted within such recess having an annular flange on one end bearing upon the face of said plate and provided with a central opening of less diameter than its body forming an interior annular shoulder, a brush projecting through such opening and having an annular flange taking against said shoulder by which the brush is maintained within the sleeve, and a spring bearing upon the flanged end of the brush.

35. 40. Signed by me this 1st day of April, 1924:
45. VANCE SHEARER.
